In France March 23, 1932

16 Claims. (Cl. 196—13)

This invention relates to a process for extracting hydrocarbon oils with organic solvents and it pertains more particularly to the use of certain oxygenated-halogen organic solvents for extracting mixed base oils and naphthas.

One object of our process is to provide a process for extracting objectionable substances from hydrocarbon oils and particularly lubricating oils, whereby the oils will have improved properties.

10 A further object of our invention is to provide a process for extracting the unsaturated and aromatic compounds from low boiling hydrocarbons such as naphthas.

15 One application of our invention provides an improved process for treating light hydrocarbon distillates, such as kerosene and burning oils, whereby the naphthenic hydrocarbons, sulfur compounds and other objectionable substances can be removed. Our extraction process is used 20 to replace the acid treatment generally applied to light hydrocarbon distillates. We may also employ our process for extracting the naphthenic and unsaturated hydrocarbons from gasoline, naphthas and particularly the cracked naphthas to obtain a concentrate of compounds that have 25 improved antiknock properties.

20 A further specific object of our invention is to provide a process for extracting objectionable substances from lubricating oils whereby the oils will have improved viscosity characteristics; for example, such as is shown by the viscosity index.

25 A further object of our invention is to provide an improved process for treating mixed base petroleum oils without the nuisance and expense 30 of acid treatment, and without the loss of valuable petroleum constituents which accompanies the use of acid treating. A further object is to provide a lubricating oil with a minimum tendency toward sludge formation when exposed to 35 oxidizing conditions. Other objects will be apparent as the detailed description of our invention proceeds.

40 The expression "viscosity index", as used herein, refers specifically to the index defined by 45 Dean & Davis in Chemical & Metallurgical Engineering, vol. 36, page 618, 1929. The viscosity index of the lubricating oil is an indication of its composition or type, that is, whether it is a paraffin base or naphthenic base oil. Paraffin 50 base oils are arbitrarily assigned a viscosity index of 100. Naphthenic base oils are assigned a viscosity index of zero, and mixed base oils lie between these extremes. When our invention is applied to mixed base lubricating oils, the object 55 is to obtain from these lubricating oils a maxi-

mum yield of paraffin-type oils (with a high viscosity index) without the nuisance or cost of acid treating, and without appreciable destruction of the naphthenic constituents of the oil.

We have discovered that certain oxygenated- 5 halogen organic compounds, such as halogenated ketones, for example, di-(2-chlorethyl) ketone; halogenated acetals, for example, dichlorethylene diethyl ether; halogenated aldehydes, for example, ortho-chlorbenzaldehyde and chloral; 10 and halogenated ketols and the like, have remarkable properties for the extraction of undesirable substances such as naphthenic compounds, from hydrocarbon oils. Examples of 15 these hydrocarbon oils are the naphthas and mixed base lubricating oils. In describing one 20 of the preferred embodiments of our invention we will illustrate in detail the use of di-(2-chloroethyl) ketone in the process of extracting the undesirable compounds from a mixed base lubricating oil. It should be understood that other 25 compounds selected from the above classes and equivalent classes of compounds may be used in the following example, instead of the chlorinated ketones, without departing from the scope of our invention. Also these chlorinated ketones may be used to extract the antiknock fraction of compounds, such as the unsaturated and naphthenic hydrocarbons, from low boiling mineral oils such as naphtha and cracked naphtha.

In the accompanying drawing which forms a part of this specification, we have shown diagrammatically, an elevational plan view of an apparatus which is suitable for carrying out our process. Our invention is applicable to the treatment of any mixed base mineral oil or naphtha, but in our preferred embodiment we have described the treatment of a heavy untreated lubricating distillate having a viscosity of about 102 seconds Saybolt at 210° F., a gravity of about 21.3 A. P. I. and a Dean & Davis viscosity index of about 58. We will also disclose the use of a batch process wherein equal amounts of the solvent and oil are mixed and separated in successive steps, but it will be apparent that we may also use a continuous process and extract the oil with the solvent counter-currently.

The mixed base lubricating oil may be introduced by a pipe 10 into extractor 11 which is provided with suitable agitating means, such as the stirrer 12. A pulley 12a is provided on the stirrer so that it may be driven by a belt or some suitable means. A closed coil 13 is provided on the inside of the extractor, said coil being provided with connections whereby it may be heated 55

with steam from pipe 14 or cooled with water, brine or a suitable refrigerant from pipe 15. The base of the extractor is preferably conical and it terminates in a discharge pipe 16 which preferably has a glass window 17 therein so that the liquids flowing through the pipe may be seen.

After the extraction, which will be described later, the solvent and naphthenic extract are withdrawn through pipe 18 and valve 19 to still 20, the extract being removed from the still through pipe 21. The solvent is distilled from the extract and passes up through the fractionating tower 22, around the reflux coils 23, through pipe 24, condenser 25, and pipe 26 to storage tank 27, from which it may be introduced into the extractor by means of pipe 28 in amounts regulated by valve 29. A suitable venting device 27a is provided on the storage tank 27. The vacuum pump 24a, which is connected in the line 24, may be used to reduce the pressure in still 20, thereby enabling the solvent to be distilled at a lower temperature than would be necessary if the distillation were performed at atmospheric pressure. It is particularly desirable to use vacuum distillation when high boiling solvents, that decompose upon heating, are used to extract the oils.

The residual oil or raffinate is withdrawn through pipe 30 and valve 31 into the stripping tower 32, which is provided with a heater coil 33 in the base thereof. A perforated pipe 33a is also inserted in the bottom of the stripper to supply a stripping gas, such as steam, carbon dioxide or some inert gas. The oil, freed from solvent, is withdrawn through pipe 34 and valve 35. The chlorinated ketone and stripping medium are removed from the stripper by pipe 36, passed to the condenser 27, and thence to the separator 38 where the stripping medium is separated from the oil. A valved vent 38a is provided on the separator to remove the condensed steam or gaseous stripping medium. The solvent is returned by the pump 39 and line 40 to storage tank 27. We introduce equal parts of the untreated viscous oil, hereinabove described, and di(2-chloroethyl) ketone into extractor 11. We then introduce steam in coils 13 to raise the temperature high enough to obtain complete miscibility between the oil and dichloracetone. In this particular example we use a temperature of about 100° F., but the temperature may vary considerably with the different oils, the preferred range being about 50-200° F. However, when our process is used to extract the antiknock fraction of hydrocarbons from low boiling oils such as naphtha, it is not necessary to heat the solvent and naphtha in order to obtain miscibility. Generally, the solvent is miscible with the naphthas at temperatures within the range of -10° to +10° F. During the first step, the oil and solvent may be thoroughly mixed by the agitator 12. In fact, if the agitation is sufficiently complete the temperature need not be raised to effect miscibility. It is very important, however, to obtain thorough contact of oil with solvent. After the solvent has been thoroughly mixed with the oil we cool the mixture to decrease the amount of oil dissolved in the extract. Cooling may be effected by passing cold water brine or other refrigerants through coils 13, the agitation being preferably continued during the cooling step. It appears that the temperature to which the mixture is cooled has a marked effect upon the yield of paraffinic-type oil and the selectivity of the solvent. The yield of oil or raffinate increases as the temperature of the mixture undergoing separation decreases.

From 35° to 95° F. this change is closely proportional in magnitude to the temperature change. At higher temperatures the decrease in yield is more rapid than the increase in temperature.

After cooling, the oil and solvent are allowed to separate, which separation may require from one-fourth hour to four or five hours at temperatures from 100° F. to 35° F., and we prefer to use the lower temperature and longer periods of separation. If the oil has not been dewaxed the upper oil layer may solidify on cooling, the lower chloracetone layer being substantially wax-free and fluid; usually both the oil and solvent will be in liquid state. The extract layer is removed by opening valves 16a and 19, and when the oil layer appears in the sight glass 17, valve 16a is closed. We then close valve 19 and open valves 16a and 31 and pass the remaining oil or raffinate into the stripping column 32, as hereinabove described. Or we may extract the oil a second time with the same solvent or a different solvent as many times as desired to effect the degree of refining required. In this case we may employ the subsequent extracts to initially treat a new batch of raw oil in the manner known to the art. Also, with highly volatile solvents, the extraction may be performed under pressure, and in such processes the pump 9 can be used to force the solvent into extractor 11. The extraction may be performed at any pressure, but preferably at a pressure within the range of one to fifty pounds per square inch.

The operating temperatures of still 20, column 22 and stripper 32, the number of fractionating plates, the amount of refluxing, etc. may be determined by anyone skilled in this art, and since they form no part of the present invention, they will not be described in detail. In fact, we may draw the oil from the top of the extractor by suitable draw-off pipes, and we may then use the extractor itself as a steam still for separating the chlorinated ketone from the extract; a suitable vapor take-off pipe and condenser being provided between the extractor and the solvent storage tank 27. Other expedients will be apparent to those skilled in the art.

Other chlorinated ketones may be used as solvents for extracting mixed base hydrocarbon oils and these chlorinated ketones may be used in substantially the same manner as described above in connection with di(2-chloroethyl) ketone. The chlorinated ketones given below are representative of the class of ketones suitable for our invention. Some of the chlorinated ketones set forth have boiling points substantially above and some have boiling points substantially below the boiling point of di(2-chloroethyl) ketone, and the miscibility of these solvents with the oil can be regulated by increasing or decreasing the temperature at which the oil is extracted. The selection of an appropriate temperature can be easily determined by those skilled in the art. Most of the ketones suitable for our invention have the general formula $R-CO-R_1$, wherein R represents an organic residue which may or may not be chlorinated, and R_1 represents a chlorinated organic residue. We may also use chlorinated diketones of the general formula $R-CO-CO-R_1$ and $R_2-CO-R_3-CO-R_2$, wherein R represents an organic residue that may or may not be chlorinated, and R_1 represents a chlorinated organic residue. R_2 , R_3 , and R_4 represent organic residues, any one of these or any combination of which may be chlorinated. We have found that the alpha monochlorinated ke-

tones are generally unstable when distilled from the oils, and we prefer to use the polychlorinated carbonyl compounds and carbonyl compounds having the chlorine atom more than one carbon atom removed from the carbonyl group, such as the beta and gamma derivatives. Examples of the chlorinated ketones that are suitable for our invention are: trichlor acetone, 2-chlorethyl methyl ketone, methyl 2-2-dichlorethyl ketone, 10 dichloro biacetyl, chloro cyclobutanone, 2-trichlorethyl methyl ketone, acetone chloroform, methyl chlorisopropyl ketone, 2-dichloropropyl methyl ketone, trichlorisopropyl methyl ketone, ethyl-2-chlor ethyl ketone, 2-chloropropyl methyl 15 ketone, ethyl 2-dichlorethyl ketone, 3-chloropropyl methyl ketone, methyl trichlorisopropyl ketone, di(2-2-dichlorethyl) ketone, methyl 3-chlorbutyl ketone, methyl 2-dichlorbutyl ketone, 2-chlorethylisopropyl ketone, ethyl trichlorisopropyl ketone, ethyl dichlorisopropyl ketone and the like.

As a further example of chlorinated compounds suitable for extracting mineral oils, such as naphthas and lubricating oils, we may use the chlorinated acetals. Most of the halogenated acetals suitable for our invention have the following general formula:

wherein R represents an alkylene residue and R₁ and R₂ represent alkyl residues, and any one combination or all three of said residues may be chlorinated. The examples of the chlorinated acetals that are suitable for our invention are: chloromethylene di(methyl ether), chloromethylene di(ethyl ether), chloro methylene di(2-chlorethyl ether), di and trichloracetals or polychloro acetals, ethyldene di(2-chlorethyl ether), ethyldene di(chloropropyl ether), chlorethylene di(methyl ether), dichlorethylene di(ethyl ether), dichlorethylene di(methyl ether), and the like.

The chlorinated aldehydes suitable for our invention have the general formula R-CHO wherein R represents a chlorinated organic residue. Examples of the chlorinated halides suitable for our invention are: mono, di and trichloracetaldehyde, 2-chloropropionic aldehyde, 2-dichloropropionic aldehyde, 2-3-dichlorbutyraldehyde, 2-3-trichlorbutyraldehyde, 2-chlorobutyraldehyde, 3-chlorbutyraldehyde, ortho, meta and para chlorobenzaldehyde and the like.

It should be understood that the compounds set forth in this application are representative of the general class of compounds suitable for our invention and that other chlorinated derivatives, homologs and isologues of the compounds set forth may be used as solvents for extracting mineral oils. Also, the compounds set forth hereinabove and their equivalents may or may not be used in the anhydrous form. Generally, the above compounds may be used in the commercial forms. As a further modification of our invention we may use mixtures of the solvents set forth above and we have found it desirable to mix those solvents which have boiling points that are substantially the same.

It should be understood that the mineral oil to be extracted, or the solvents, may be mixed with other solvents or diluents such as propane, butane, propylene, naphtha, acetone, etc. for the purpose of effecting a better and quicker separation of the liquid phases. Also, these diluents tend to reduce the viscosity of the oil and en-

hance the solvent action of the particular solvent used. When the very light diluents are used, such as propane and butane, we may evaporate a portion thereof to obtain cooling whenever desired. This step is particularly useful for cooling the oil in the extractor 11. By flashing a quantity of the propane with the aid of a suitable vent disposed in the top part of the extractor 11, we can effect sufficient cooling so that it will not be necessary to employ the cooling coils 13. Chlorinated hydrocarbons, such as ethylene dichloride and the like, may also be used in combination with the solvents hereinabove described.

The volume of solvent used to extract the oil may vary with the selectivity of the particular solvent; however, from one to two volumes of solvent for each volume of oil will give satisfactory results. It should be understood that larger volumes, for example four or five volumes, of solvent may be used for each volume of oil. When mixed solvents are used to extract a lubricating oil we may use equal proportions of the solvent or we may use more of one solvent than the other.

We do not limit ourselves to any theory or explanation of why the compounds set forth hereinabove are suitable extracting agents, but experiments have shown that the above general classes of compounds are in a class by themselves and that they produce results of an entirely different order from the results produced by other well known solvents.

Instead of using the extraction process as a sole means for treating the oil, it may be used to supplement a preliminary acid treatment. The preliminary acid treat may, for instance, be desirable for separating the tarry materials that would be undesirable in the naphthenic extract.

We preferably follow the extraction process with a light sulfuric acid treat to improve color. Also the oil may be clay treated, such as by percolation or contacting with fine clay at elevated temperatures in order to improve the color and sludge stability of the oil. If the oil was initially dewaxed, it will be in a finished condition after the clay treatment.

A very important characteristic of the oils produced by our improved extraction process is their ability to resist oxidation and sludge formation. This abnormal freedom from sludge formation is probably due to the removal of certain potential sludge-forming ingredients in the oil, and while we do not understand the exact phenomena, experiments have proved the superior sludge resistant properties of our finished lubricating oil. For instance, an oil which, when acid treated, has a sludge time of about 22 hours and a deterioration time of 47 hours has, when extracted in accordance with our invention, a sludging time of more than 60 hours and a deterioration time of more than 125 hours. Many modifications of our invention will be apparent to those skilled in the art, for instance, we may heat a mixture of oil and solvent to a miscibility temperature (say 150° F.) and then, instead of making a single separation, we may separate the oil in consecutive steps as the temperature is lowered (say at 135° F., 80° F. and 35° F.). The final separation temperature may be below the pour point of the oil layer.

As stated above, the solvents and processes set forth hereinabove may be used to extract naphthas, kerosene, gasoline and the like for the purpose of removing the naphthenic and unsaturated compounds in these hydrocarbon distillates.

When our process is used to extract the antiknock substances from naphtha, the process is substantially the same as that set forth hereinbefore in connection with the extraction of lubricating oils.

5 The solvent is distilled from the extract in still 20 and the solvent is removed from the raffinate in the stripper 32 in the same manner as herein described. The solvent used for extracting the naphtha should preferably boil at about or somewhat 10 below the initial boiling point of the naphtha or cracked hydrocarbon oil. For example, if the naphtha has an initial boiling point within the range of about 250° to 350° F. and an end boiling point within the range of 360° to 400° F., the 15 boiling point of the solvent should be somewhat below the initial boiling point of said naphtha.

As a modification of our process, we may extract naphthas with solvents that boil above the end point of the naphtha. For example, if the naphtha has an end point within the range of 200° to 20 280° F., we may use a solvent that boils above the end point of said naphtha. In this modification of our invention it is apparent that the extract must be distilled from the solvent in still 25 20. Similarly, the raffinate is distilled from the solvent in the stripper 32. The conduit 26 is disconnected from the tank 27 and diverted to a storage tank, not shown, for collecting the extract. Similarly, the conduit 40 is disconnected 30 from tank 27 and diverted to a storage tank, not shown, to collect the raffinate. The solvent is removed from conduits 21 and 34 and returned to the tank 27 for further use in the extraction of the oils.

35 As a second modification of our invention, the naphthas may be extracted with solvents that boil at a temperature between the initial and end boiling point of the naphtha. In such cases the solvent and extract or solvent and raffinate cannot 40 be separated by distillation and other methods must be adopted to separate the solvent from the extract and raffinate. For example, a 50 to 80% solution of methyl or ethyl alcohol or other suitable solvents may be added to the extract layer 45 in order to effect a separation of the solvent from the extract.

Although the details of our invention have been described by giving examples of processes for extracting mixed base lubricating oils, it should be 50 understood that anyone skilled in the art can modify the above examples and extract the light hydrocarbon distillates according to the teachings of this invention. While we have described the preferred embodiment of our invention, it should 55 be understood that we do not limit ourselves to any of the details hereinabove set forth, except as defined by the following claims which should be construed as broadly as the prior art will permit.

60 We claim:

1. The method of removing naphthenic compounds and unsaturated compounds from a mixed base lubricating oil which comprises heating and agitating the oil with a polychlorinated 65 organic compound containing a carbonyl group, cooling the oil and solvent until separation of paraffinic compounds from the solvent and dissolved compounds occurs, and separating the solvent together with the dissolved compound from 70 the treated oil.

2. The method of preparing lubricating oils having a high viscosity index and which are stable against sludge formation, which comprises mixing a mixed base lubricating oil with an organic solvent selected from the group consisting 75

of polychlorinated ketones containing not more than six carbon atoms, chlorinated aldehydes containing not more than four carbon atoms and chlorinated acetals containing not more than eight carbon atoms, heating the oil and solvent to obtain substantial miscibility, cooling said mixture of oil and solvent until separation of paraffinic compounds from the solvent and dissolved compounds occurs, and separating the solvent together with the dissolved compounds from the treated oil. 10

3. The method of extracting unsaturated compounds from a mineral oil distillate containing unsaturated compounds and paraffinic compounds, which comprises mixing the oil with an organic solvent selected from the group consisting of polychlorinated aliphatic ketones containing not more than six carbon atoms, chlorinated aliphatic aldehydes containing not more than four carbon atoms and chlorinated aliphatic acetals containing not more than eight carbon atoms, cooling the mixture of oil and solvent until separation of paraffinic compounds from the solvent and dissolved unsaturated compounds occurs, and separating the solvent together with the dissolved compounds from the treated oil. 15 20

4. The method of extracting unsaturated hydrocarbons from a hydrocarbon oil distillate containing unsaturated hydrocarbons and paraffinic hydrocarbons, which comprises mixing the distillate with a polychlorinated aliphatic ketone containing not more than six carbon atoms, cooling said mixture of distillate and solvent until separation of paraffinic hydrocarbons from the solvent and dissolved unsaturated hydrocarbons occurs, and separating the solvent together with the dissolved hydrocarbons from the treated hydrocarbon oil distillate. 30 35

5. The method of extracting unsaturated hydrocarbons from a hydrocarbon oil distillate containing unsaturated hydrocarbons and paraffinic hydrocarbons, which comprises mixing said oil with a solvent containing a beta-chlorinated aliphatic ketone containing not more than six carbon atoms, cooling the mixture of oil and solvent until separation of paraffinic compounds from the solvent and dissolved unsaturated compounds occurs, and separating the solvent together with the dissolved compounds from the treated oil. 40 45

6. The method of extracting unsaturated compounds from a mineral hydrocarbon oil distillate containing unsaturated compounds and aliphatic compounds, which comprises mixing the oil with an organic solvent containing a beta-chlorinated carbonyl compound containing not more than eight carbon atoms, cooling the mixture of oil and solvent until separation of paraffinic compounds from the solvent and dissolved unsaturated compounds occurs, and separating the solvent together with the dissolved compounds from the treated oil. 55 60

7. The method of removing naphthenic compounds and unsaturated compounds from a mixed base lubricating oil which comprises contacting a mixed base lubricating oil with a solvent containing a chlorinated aldehyde containing not more than four carbon atoms, heating and agitating the oil and solvent to obtain substantial miscibility, cooling the oil and solvent until separation of paraffinic compounds from the solvent and dissolved compounds occurs, and separating the solvent together with the dissolved compounds from the treated oil. 65 70

8. The method of removing naphthenic compounds from a mixed base lubricating oil which 75

- comprises heating and agitating the oil with a polychlorinated aliphatic aldehyde containing not more than four carbon atoms, cooling the oil and solvent until separation of paraffinic compounds 5 from the solvent and dissolved naphthenic compounds occurs, and separating the solvent together with the dissolved naphthenic compounds from the treated oil.
9. The method of removing naphthenic compounds from a mixed base lubricating oil, which 10 comprises heating and agitating the oil with a solvent containing a beta-chlorinated aliphatic aldehyde containing not more than four carbon atoms, cooling the oil and solvent until separation 15 of paraffinic compounds from the solvent and dissolved naphthenic compounds occurs, and separating the solvent together with the dissolved naphthenic compounds from the treated oil.
10. The method of extracting unsaturated hydrocarbons from a hydrocarbon oil distillate containing unsaturated hydrocarbons and paraffinic hydrocarbons, which comprises mixing the oil with a solvent containing a chlorinated aldehyde containing not more than four carbon atoms, 20 cooling the mixture of oil and solvent until separation of paraffinic hydrocarbons from the solvent and dissolved unsaturated hydrocarbons occurs, and separating the solvent together with the dissolved compounds from the treated oil.
- 30 11. The method of extracting unsaturated compounds from a mineral hydrocarbon oil distillate containing unsaturated compounds and aliphatic compounds, which comprises mixing the oil with a solvent containing a beta-chlorinated aliphatic aldehyde containing not more than four carbon atoms, cooling the mixture of oil and solvent until separation of paraffinic compounds from the solvent and dissolved unsaturated compounds occurs, and separating the solvent together with the dissolved unsaturated compounds from the treated oil.
12. The method of removing naphthenic compounds from a mixed base lubricating oil, which 45 comprises heating and agitating the oil with a solvent containing a chlorinated acetal containing not more than eight carbon atoms, cooling the oil and solvent until separation of paraffinic compounds from the solvent and dissolved naphthenic compounds occurs, and separating the solvent together with the dissolved compounds from the treated oil.
- 50 13. The method of extracting unsaturated hydrocarbons from a mineral hydrocarbon oil distillate containing unsaturated hydrocarbons and
- paraffinic hydrocarbons, which comprises mixing the oil with a solvent containing a chlorinated acetal containing not more than six carbon atoms, cooling said oil and solvent until separation of paraffinic hydrocarbons from the solvent and dissolved unsaturated hydrocarbons occurs, and separating the solvent together with the dissolved unsaturated hydrocarbons from the treated oil. 5
14. The method of extracting unsaturated compounds from a hydrocarbon oil distillate containing unsaturated compounds and aliphatic hydrocarbons, which comprises mixing the oil with an organic solvent containing a polychlorinated aliphatic acetal containing not more than six carbon atoms, cooling the mixture of oil and solvent until separation of paraffinic compounds from the solvent and dissolved unsaturated compounds occurs, and separating the solvent together with the dissolved compounds from the treated oil. 10
15. The process of extracting unsaturated hydrocarbons from petroleum naphtha containing unsaturated hydrocarbons and paraffinic compounds, which comprises mixing the naphtha with an organic solvent selected from the group consisting of polychlorinated aliphatic ketones containing not more than six carbon atoms, chlorinated aliphatic aldehydes containing not more than four carbon atoms and chlorinated aliphatic acetals containing not more than six carbon atoms, cooling the mixture of naphtha and solvent until separation of paraffinic compounds from the solvent and dissolved unsaturated hydrocarbons occurs, and separating the solvent together with the dissolved unsaturated hydrocarbons from the treated naphtha. 15
16. The method of preparing lubricating oils having a high viscosity index and which are stable against sludge formation, which comprises mixing a mixed base lubricating oil with a beta chlorinated aliphatic ketone containing not more than six carbon atoms, heating the oil and chlorinated ketone to obtain substantial miscibility, cooling said mixture of oil and chlorinated ketone until separation of paraffinic compounds from the chlorinated ketone and dissolved compounds occurs, separating the chlorinated ketone together with the dissolved compounds from the treated oil. 20
